UNITED STATES PATENT OFFICE.

ALBERT E. ZIMMER, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

DUMP-CAR SAFETY FOOT-GUARD.

1,164,902.

Specification of Letters Patent. Patented Dec. 21, 1915.

Application filed March 12, 1915. Serial No. 13,846.

To all whom it may concern:

Be it known that I, ALBERT E. ZIMMER, a citizen of Norway, residing at Chicago, in the county of Cook and State of Illinois, have invented a certain new and useful Improvement in Dump-Car Safety Foot-Guards, of which the following is a full, clear, concise, and exact description, reference being had to the accompanying drawings, forming a part of this specification.

This invention relates to improvements in dump car safety foot guards.

In the unloading of dump cars, and more particularly that type of dump cars having hinged side dump floor doors, it has been found that injury often results to the foot of the operator, due to the fact that while standing on the step ladder at the end of the car, the floor doors are released with the full weight of the load thereon which doors, in swinging downwardly catch and injure the toe of the operator's foot which extends through the step ladder into the path of the door or some part carried thereby.

The object of my invention is to provide simple, efficient and inexpensive means adaptable to all types of dump cars where the above described difficulties are encountered, and which will effectively prevent injury to the operators and which at the same time will be in full compliance with all regulations of the Interstate Commerce Commission and other bodies which regulate railway practice.

In the drawing forming a part of this specification, Figure 1 is a side elevation of an end portion of a dump car showing my improvements in connection therewith. Fig. 2 is a vertical sectional view taken substantially on the broken line 2—2 of Fig. 1 and looking in the direction of the arrows and Fig. 3 is a detail perspective view of the foot guard proper.

In said drawing the side wall of the dump car is designated generally by the reference A, the same consisting of a vertical portion 10 and inwardly inclined lower portion 11, the bottom of which forms a meeting edge 12 for the outer free edge of the hinged, side dump, floor doors 13, which doors are pivoted at their inner edges as indicated at 14 adjacent the center sill construction 15. As is usual, a series of hand-grabs 16—16 are secured to the side of the car at the right hand end, as viewed by the observer, and

below the hand-grabs is a step ladder B which consists of side straps 17 and 18, lower step 19 and next higher step 20, said steps being arranged vertically, in the usual manner, and below the normal floor level of the car (see Fig. 2).

In the construction which I have shown, the floor doors are operated by a well known door operating mechanism, the same including a longitudinally extending operating shaft 21. Each mechanism consists of a hub 22 secured to the shaft, each hub having a link 23 pivotally connected therewith. For each operating mechanism each door 13 is provided with an extended bracket or arm 24 to which is adjustably pivotally connected a hook 25. Pivotally connected to the hook 25 and to the link 23 are a series of pivotally connected links 26, 27 and 28, the arrangement being such that when the doors are in closed position, the hook 25 rests upon the hub attached to the shaft and thus relieves the strain on the link mechanism. In Fig. 2, the dotted line 29 indicates the path of travel of the outermost portion secured to the door, and as will be observed by viewing Fig. 1, this path of travel is directly behind the step ladder.

Heretofore, the operator has been injured by placing his foot upon the step 20 and extending it through the ladder to such an extent that when the door operating mechanism is released and the end door is allowed to fall with the load thereon, the extension on the particular door shown (and the door itself in those constructions where the floor door extends out to the vertical plane of the side of the car,) catches the operator's foot and thereby causes injury. To obviate this, I have provided a guard designated generally by the reference C, which, as shown, comprises a plate having an upper inclined portion 30, short vertical section 31 and horizontal portion 32, the latter being secured to the lower step 19, and the upper portion 30 being riveted or otherwise suitably secured to a cross strap 33 which is riveted at its ends to the side members 17 and 18 of the steps. As shown in the drawing, the guard C is of a width approximating that of the end door operating mechanism, as this is all that would be required in the particular construction shown. In other constructions, however, where the door itself is extended substantially to the verti-

cal plane of the side of the car, the foot guard would be made wider and even as wide as the steps themselves, in order to prevent the operator from sticking his foot 5 through the ladder into the path of the downwardly swinging door or part attached thereto.

As clearly shown in Fig. 2, there is sufficient clearance provided by the foot guard 10 to permit the operator to put his foot on the lower and next higher step to secure a firm foot hold. At the same time there is provided sufficient clearance between the guard and the arm of the door to comply with Interstate Commerce Commission regulations. 15

It will be obvious to those skilled in the art that my improvements may be embodied in other structures than those herein shown, the foot guard herein shown and described 20 being designed more particularly for one type of car. I do not wish to be confined, therefore, to the specific construction herein shown and described, but contemplate all changes and modifications that come within 25 the scope of the claims appended hereto.

I claim:

1. In a dump car provided with a ladder and a hinged door, the edge of which is movable in a path adjacent to said ladder, a foot 30 guard located on the inner side of the steps of said ladder and in the clearance of said door edge, whereby to prevent an operator from projecting his foot through the ladder into the path of said hinged door.
35. 2. The combination with a dump car having a movable, side dump, floor door and a side ladder adjacent the path of movement of said door, of a foot guard strip located on the side of the ladder nearest said door 40 adapted to prevent an operator from projecting his foot through the ladder to a position in the path of the movable door.
45. 3. In a dump car having a hinged door, the combination with steps adjacent the path of movement of said door, of a guard plate located between the path of movement of said door and said steps.
4. The combination with a dump car hav-

ing a swinging dump door, of steps located adjacent said door and below the normal load carrying position thereof, and a guard plate secured to said steps on the side adjacent the door and in the clear of the door and all parts movable therewith as the latter swings.

5. A device of the character described comprising a railway car step ladder having a plurality of steps and a plate attached thereto, said plate being located on the inner side of said steps and extending vertically 60 past the same and arranged to limit the amount to which an operator's foot can be extended through the ladder on any step, said plate being of less width than the width of the ladder.

6. The combination with a dump car having a hinged, side dump, floor door, and operating mechanism for said door, of a step ladder secured to the side of said car near one end thereof, and located below the normal, load carrying position of said door, and a guard plate secured to said steps on the inner side thereof, said guard plate limiting the amount to which an operator may extend his foot through the step ladder in 75 front of the door operating mechanism.

7. The combination with a dump car having a hinged, side dump, floor door, and operating mechanism therefor, of a step ladder secured to the side of the car near one end 80 thereof, said door and the operating mechanism therefor being movable in a path in the rear of said step ladder when the door swings downwardly, and a foot guard, said foot guard comprising a transversely extending strip secured to the step ladder and a plate having the upper end thereof secured to said strip and its lower end secured to the lower step of the ladder.

In witness that I claim the foregoing I 90 have hereunto subscribed my name this 27th day of Feb. 1915.

ALBERT E. ZIMMER.
